UNITED STATES PATENT OFFICE.

LEOTA POST, OF KENNETH, MISSOURI.

DESIGN FOR A STUFFED TOY ANIMAL.

Application filed July 11, 1924. Serial No. 10,122. Term of patent 14 years.

To all whom it may concern:

Be it known that I, LEOTA Post, a citizen of the United States of America, residing at Kennett, in the county of Dunklin and State of Missouri, have invented a new, original, and ornamental Design for a Stuffed Toy Animal, of which the following is a specification, reference being had to the accompanying drawing, forming a part hereof.

The figure is a perspective view showing my new, original and ornamental design for a stuffed toy animal.

I claim:—

The ornamental design for a stuffed toy animal as shown.

LEOTA POST.
